(57) **CLAIM**

We claim the ornamental design for a display screen with graphical user interface for a beverage dispenser, as shown and described.

DESCRIPTION

FIG. 1 is a front view of a display screen with graphical user interface showing the new design;

FIG. 2 is a front view of a display screen with graphical user interface showing an alternative embodiment thereof; and, FIG. 3 is a front view of a display screen with graphical user interface showing an alternative embodiment thereof.

The even-length broken lines showing the remainder of the beverage dispenser are for environmental purposes only and form no part of the claimed design.

1 Claim, 3 Drawing Sheets
